UNITED STATES PATENT OFFICE.

WILLIAM WADDELL, OF LONDON, ENGLAND, ASSIGNOR TO INTERNATIONAL HARVESTER COMPANY, OF CHICAGO, ILLINOIS, A CORPORATION OF NEW JERSEY.

GRAIN SHOCKER

Application filed July 18, 1923. Serial No. 652,223.

My invention relates to grain shocking machines and particularly to mechanism for properly building and setting a shock in the field.

5 One of the objects of my invention is to provide an improved means for properly building a shock in the receptacle of a shocker.

A further object of the device is to provide an improved construction by means of which the butts of the sheaves will be adequately spread before they are placed in the receptacle.

10 A further object of the device is to provide means for maintaining the butts in a separated or diverging position in the receptacle.

15 A further object of the invention is to provide a device for simultaneously depositing a plurality of sheaves in a receptacle with the butts of the sheaves diverging and the heads converging.

20 A still further object of the invention is to provide means for automatically spreading the butts of a plurality of sheaves during the time they are being conveyed from the binder deck of the harvester to the receptacle of the shocker.

25 These and other objects are attained by 30 providing a novel construction of a sheaf delivery member adapted to co-operate with a divider in the receptacle in such a manner that the shock is built in the receptacle with the butts adequately spread so as to insure 35 complete ventilation or drying out of the grain in the shock.

30 Referring to the drawings, Fig. 1 is a top plan view of a grain shocker showing my improvement embodied therein.

40 Fig. 2 is a side elevational view of the grain shocker shown in Fig. 1.

45 Fig. 3 is a rear elevational view of the grain shocker showing the manner in which two sheaves are deposited by the sheaf delivery member with one sheaf deposited on each side of the divider simultaneously.

50 Fig. 4 is an enlarged detail and side elevational view of my improved sheaf delivery member showing it in its normal sheaf receiving position beneath the deck and the discharging mechanism of the grain binder.

55 Fig. 5 is an enlarged top plan view of my improved sheaf delivery member showing the construction by which the sheaves are separated or spread at their butts prior to being deposited in the shock receptacle.

Fig. 6 is an enlarged front elevational view of my improved sheaf delivery member showing it in the same position as in Fig. 4, and

60 Fig. 7 is a detail view showing the shock receptacle in its tilted position of delivering or setting a shock upon the ground and showing the position the divider assumes when the shock is deposited on the ground.

65 My improved butt spreading mechanism is shown embodied in the general type of grain shocker shown and described in U. S. Letters Patent to Raney No. 1,293,922, dated Feb. 11, 1919, which comprises the usual

70 main frame 10 mounted on the carrying wheels 11 by the channel members 12. Secured to and extending upwardly from the main frame member 10 are the front and rear supplemental frame members 13 and

75 14, respectively. Secured to the front supplemental frame member 13 and extending transversely with respect to the shocker is an upper frame member 15. Mounted on the

76 stubbleward side of the grain shocking machine and journaled in suitable bearings secured to the supplemental frame members

80 13 and 14 is the usual needle shaft 16 having a needle 17 secured thereto. Mounted on the grassward side of the shocker and

85 journaled in suitable bearings 18 and 19 is the usual knotter shaft 20 with the knotter mechanism 21 mounted thereon. It will be understood that the needle and knotter mechanism is connected by a pitman not

80 shown.

85 Secured to the main frame 10 and extending across the rear ends thereof is the usual shock receptacle pivot shaft 22 having pivotally mounted thereon for upward and rearward movement with respect thereto, the

90 usual shock receptacle 23. The shock receptacle 23 is actuated to swing upwardly and rearwardly in the normal operation of setting a shock through a crank shaft mechanism,

95 which comprises a crank 24 having a roller 25 adapted to engage the lower side of the receptacle 23. The crank 24 is formed integrally with a shaft 26 which is journaled by means of bearing brackets 27 on

100 the supplemental frame member 14. The shaft 26 is actuated through a gravity latch mechanism, which comprises a crank 28

journalled on the shaft 26 and a gravity pawl 29 pivoted to the crank 28 and adapted to engage a second crank 30 secured to the grassward end of the shaft 26. The crank 28, in turn, is actuated through a pitman connection 31 which is operatively driven by a crank 32 secured to the knotter shaft 20. The sheaves as they are deposited in the shock receptacle are held against longitudinal displacement by vertically extending tines 33 secured to the tine shaft 34 which is pivoted to the shock receptacle by means of pivot brackets 35. The tines 33 are normally held in their vertical position or the positions shown in Figs. 2 and 3 by an extension spring 36 having one end thereof secured to a crank portion 37 formed on the pipe 34 and the other end thereof secured to the shocker frame. The shock tieing mechanism including the needle and the knotter together with the shock discharging mechanism thus far described is the usual mechanism used in this type of grain shucker and per se does not form any part of the present invention. The mechanism for conveying or delivering the sheaves discharged from the binding mechanism of the harvester to the shock receptacle of the shucker comprises a sheaf delivery member 38 journalled on a shaft 39 by means of a bracket 40. The bracket 40 is connected to the sheaf delivery member 38 by straps 41, one of which is reinforced by a brace 42. The shaft 39 is secured to oppositely disposed supplemental frame members 43 and 44 which have their lower ends secured to the main frame 10 at 45 and 46, and their upper ends secured to the transverse frame member 10 at 47 and 48. The sheaf delivery member is actuated to deliver the sheaves from the binder deck of the harvester to the receptacle off the shucker or in other words, is actuated from the full line position shown in Fig. 1 to the dotted line position by a pitman connection 49 having its upper end pivotally connected to a crank 50. The lower end of the pitman is connected to a crank 51 which is intermittently actuated by a clutch and pawl mechanism 52. The intermittent clutch mechanism 52 is adapted to be connected with the continuously operating clutch mechanism 53 when the tripping mechanism 54 is tripped, that is, when two sheaves are discharged by the discharge mechanism of the grain binder. The continuously operating clutch mechanism 53 is continuously driven by a shaft 55 which in turn derives its power from the grain binder through a series of connections not shown in these drawings. The construction of this mechanism for actuating and tripping the sheaf delivery member is described and claimed in the U. S. patent to Raney No. 1,293,922, dated Feb. 11, 1919, and per se does not form any part of the present invention, and therefore a more de-

tailed description of this mechanism is thought not necessary.

The mechanism which forms a part of the present invention comprises a divider 56 shown in the form of an inverted V which is pivotally mounted at 57 to brackets 58 secured to the shock receptacle 23. The divider comprises a transverse shaft 59 extending across the shock receptacle 23 and having its outer ends bent downwardly at right angles so as to form cranks 60. The free ends of the cranks 60 are connected by means of springs 61 to the rearward sides of the receptacle 23 by clips 62. The divider 56 is securely fixed to the shaft 59 at 63 in any well known manner. The spring 61 normally acts to return the divider 56 to its vertical position and permits the same to yield with respect to the shock receptacle 23 when the shock receptacle returns from depositing a shock upon the ground in a manner to permit the withdrawal of the divider from beneath the shock. The divider 56 has formed integrally therewith a stop 64 which is adapted to engage a cross bar 65 secured to the receptacle 23 for normally maintaining the divider in its vertical position. The divider 56 is provided with a shield 66 and a loop 67. The loop 67 is secured to the forward side of the divider 56 and extends above the same in a manner to engage the butts of the sheaves as they are being deposited in the shock receptacle.

From the construction just described, it will be seen that as the sheaves are deposited on both sides of the divider in the receptacle they will be maintained in a separated or diverging position during the time the shock is being built.

Co-operating with my improved sheaf dividing mechanism I have provided an improved sheaf delivery mechanism in which the sheaves are separated or divided in such a manner that the butts of the sheaves diverge and the heads converge prior to being deposited in the receptacle. This mechanism comprises the sheaf delivery member 38 having upper and lower plates 68 secured thereto by means of bolts 69. The forward end of the plates 68 increases in width as shown at 70. Pivotally mounted in these plates 68 by means of bolts 71 are two oppositely positioned and separately actuated forks 72. The forks 72 are adapted to swing from a closed position or the position shown in Figs. 1, 4 and 6 to the position shown in the dotted lines in Fig. 1 and in Figs. 3 and 5. The forks 72 are actuated to swing to their spread positions by extension springs 73 having one end secured to the sheaf delivery tine member 74 fixed to the member 38 and their other ends connected to tines 75 secured on the opposite sides of the forks 72. The forks 72 are limited in their outward movement by bolts 71 which extend through

the plates 68. The outer ends of the forks 72 are provided with tines 76. These tines 75 and 76 as well as the tine 74 secured to the sheaf delivery member 38 are adapted to engage the sheaves and penetrate the same after they are discharged from the binding mechanism of the harvester. Secured to the fork 72 on the opposite sides thereof and intermediate the tines 75 and 76 by means of 10 bolts 77 are cam plates 78. The cam plates 78 are adapted to engage corresponding curved plates 79, one of which is secured to the deck extension 80 of the shocker and the other of which is secured to sheaf support 15 angle 81. The lower ends of these cam plates 79 are secured by means of bolts 82 to the sheaf delivery member support 83. It will be seen by referring to Fig 4 that the cam plates 78 are curved concentrically with respect to the shaft 39 or the axis of the sheaf delivery member 38 in such a manner that as the sheaf delivery member is oscillated about its axis in delivering sheaves and returning to its normal sheaf receiving position 20 it will engage the corresponding cam plates 79.

From the construction just described it will be understood that the cam plates 78 engage the curved cam plates 79 when the 30 sheaf delivery member 38 is returning to its normal sheaf receiving position or the position beneath the binder deck of the harvester in such a manner that the forks 72 will be compressed or closed against the tension of the springs 73 and when two sheaves are discharged by the binding mechanism of the harvester upon the forks 72, the tines 75 and 76 of the forks 72 will penetrate the two sheaves in their parallel position. After 35 the sheaf delivery member 38 is oscillated about its pivot on the shaft 39 to a position in which the cam plates 78 of the forks 72 become disengaged from the cams 79, the extension springs 73 actuate the forks 72 about their pivot 71 in such a manner as to cause the butts of the two sheaves on the sheaf delivery member to diverge and the heads to converge, in which position the sheaves are deposited on the opposite sides of the divider 56, as clearly shown in Fig. 3. Obviously 40 the divider will further spread the butts of these sheaves and maintain them in a spread position during the time the shock is being built and tied by the knotter mechanism.

55 The forward end of the shocker is connected to and supported on a pipe 84 which has its grassward end secured to the main frame of the harvester beneath the binding mechanism (not shown). The forward end of the shocker is supported on this pipe 84 by a tongue 85 secured at 86 to the main frame 10. The tongue 85 has its forward end bent up at right angles with respect to the main body portion, as shown at 87 in a

manner to support the supplemental deck 80, 65 which forms an extension of the binder deck of the harvester and over which the sheaves are discharged from the binding mechanism of the harvester to the sheaf delivery member 38. 70

In order to properly support the sheaves in position to be engaged and penetrated by the tines 75 and 76 of the forks 72 the usual sheaf supports 88 are provided which are secured to the angle 81 at proper intervals 75 as shown in Fig. 1, and also to the deck supporting angle 81' as shown in Fig. 6.

In the operation of my improved butt spreading mechanism it will of course be understood that the shocker is provided 80 with the usual tripping mechanism for tripping the knotter mechanism into operation when the shock has reached the predetermined size. This mechanism is shown and described in Raney's U. S. Patent No. 85 1,231,195, dated June 26, 1917, and does not form any part of the present invention and therefore it was not thought necessary to describe the same.

When two sheaves are discharged by the 90 binding mechanism of the harvester they are conveyed or discharged over the deck extension 80 in parallel relation and supported on the supports 88. As they are conveyed to this position they trip the tripping mechanism 54, which in turn trips the continuously operating clutch mechanism 53 and connects the same with the intermittently operating clutch member 52, and thereby, through the pitman connection 49 and the 95 crank 50 actuates the sheaf delivery member 38 about its pivot on the shaft 39 to deliver the sheaves from the binder deck of the harvester to the receptacle 23 of the shocker. As the sheaf delivery member 38 is raised 100 or oscillated about its pivot on the shaft 39 to a position in which the cam plates 78 disengage corresponding cam plates 79, the extension springs 73 actuates the forks 72 about their pivots 71 and causes the butts 105 of the sheaves positioned on these forks to assume a diverging position and their heads a converging position, in which position they are delivered into the receptacle 23 of the shocker. This operation is repeated until 110 the sheaves in the receptacle have reached a predetermined height at which time the binding mechanism is tripped into operation and the needle mechanism is actuated to tie a band around the shock, at which time receptacle 23 is actuated through the pitman 115 31, crank 28 and second crank 30 to swing upwardly and rearwardly and deposit the shock upon the ground. As the receptacle 23 is actuated to swing upwardly and rearwardly the divider 56 mounted on the receptacle 23 is also actuated or swung to the 120 position shown in Fig. 7 in which the divider 125

56 assumes a horizontal position beneath the shock with the springs 61 permitting the divider 56 to yield with respect to the shock receptacle in such a manner that the receptacle 23 may assume its normal sheaf receiving position during the time the divider is being withdrawn from the shock set on the ground.

What I claim as my invention and desire 10 to secure by Letters Patent is:

1. A shocking machine, comprising a frame, a shock receptacle mounted on said frame, means mounted on said frame for delivering a plurality of sheaves into said receptacle, and means for spreading the butts of said sheaves during the delivery of said sheaves to said receptacle.

2. A shocking machine, comprising a frame, a shock receptacle mounted on said frame, means mounted on said frame for delivering a plurality of sheaves into said receptacle, and means for automatically spreading the butts of said sheaves during the delivery of said sheaves to said receptacle.

3. A shocking machine comprising a frame, a shock receptacle carried by said frame, and single means mounted on said frame for delivering and spreading the sheaves in said receptacle.

30 4. A shocking machine comprising a frame, a shock receptacle carried thereby, a sheaf delivery member pivotally mounted on said frame for delivering sheaves in said receptacle, and means carried by said sheaf delivery member for automatically spreading the butts of a plurality of sheaves simultaneously.

5. A shocking machine comprising a frame, a shock receptacle thereon, a deck, a 40 swinging sheaf delivery member pivotally mounted on said frame for delivering a plurality of sheaves from the deck into said receptacle, and means carried by the delivery member for spreading the butts of the sheaves while said member moves the sheaves from the deck to the receptacle.

6. A shocking machine comprising a frame, a shock receptacle thereon, a deck, a swinging sheaf delivery member pivotally mounted 50 on said frame for delivering a plurality of sheaves from the deck into said receptacle, and spring actuated means carried by the delivery member for spreading the butts of the sheaves while said member moves the sheaves from the deck to the receptacle.

7. A shocking machine comprising a frame, a shock receptacle carried thereby, a sheaf delivery member pivotally mounted on said frame for delivering sheaves in said receptacle, and spring actuated means carried by said sheaf delivery member for automatically spreading the butts of a plurality of sheaves simultaneously.

60 8. A shocking machine comprising a

frame, a shock receptacle carried thereby, a sheaf delivery member pivoted to said frame for delivering sheaves into said receptacle, and means including oppositely disposed members pivoted to said sheaf delivery member for spreading the butts of the sheaves 70 as they are delivered into said receptacle.

9. A shocking machine comprising a frame, a shock receptacle carried thereby, a sheaf delivery member pivoted to said frame for delivering sheaves into said receptacle, 75 and means including spring actuated, oppositely disposed members pivoted to said sheaf delivery member for spreading the butts of the sheaves as they are delivered into said receptacle.

10. A shocking machine comprising a frame, a shock receptacle carried thereby, means mounted on said frame for delivering a plurality of sheaves thereto simultaneously, and means carried by said delivery means 85 for causing the butts of the sheaves to diverge and the heads to converge.

11. A shocking machine comprising a frame, a shock receptacle carried thereby, means mounted on said frame for delivering a plurality of sheaves thereto simultaneously, and spring actuated means carried by said delivery means for causing the butts of the sheaves to diverge and the heads to converge.

12. A shocking machine comprising a frame, a shock receptacle carried thereby, means mounted on said frame for delivering a plurality of sheaves thereto simultaneously, and means for causing the butts of the sheaves to diverge and the heads to converge during the time they are being delivered by said delivery means.

13. A shocking machine comprising a frame, a shock receptacle carried thereby, means mounted on said frame for delivering a plurality of sheaves thereto simultaneously, and spring actuated means for causing the butts of the sheaves to diverge and the heads to converge during the time they are being delivered by said delivery means.

14. A shocking machine, comprising a frame, a shock receptacle carried thereby, means mounted on said frame for delivering a plurality of sheaves thereto simultaneously, means carried by said delivery means for causing the sheaves to diverge at the butts and converge at the heads while being delivered, and means mounted in said receptacle for maintaining the butts of the sheaves in their diverging positions.

15. A shocking machine, comprising a frame, a shock receptacle carried thereby, means mounted on said frame for delivering a plurality of sheaves thereto simultaneously, means carried by said delivery means for causing the sheaves to diverge at the butts and converge at the heads while being de-

livered, and a divider in said receptacle for maintaining the butts of the sheaves in their diverging positions.

16. A shocking machine, comprising a frame, a shock receptacle carried thereby, means mounted on said frame for delivering a plurality of sheaves thereto simultaneously, means carried by said delivery means for causing the butts of the sheaves to diverge and the heads to converge during the delivery of the sheaves to said receptacle, and a divider pivoted to said receptacle for maintaining the butts in their diverging positions.

17. A shocking machine comprising a frame, a shock receptacle carried thereby, a sheaf delivery member pivoted to said frame for delivering a plurality of sheaves thereto simultaneously, a divider pivotally mounted in said receptacle, and means including two members pivoted to said sheaf delivery member for spreading the sheaves and delivering them on opposite sides of said divider simultaneously.

18. A shocking machine comprising a frame, a shock receptacle carried thereby, a butt divider pivotally mounted on said shock receptacle, and single means for spreading sheaves and delivering them on opposite sides of said divider simultaneously.

19. A shocking machine comprising a frame, a shock receptacle carried thereby, a butt divider mounted on said shock receptacle, and single means pivoted to said frame

for spreading sheaves and delivering them on opposite sides of said divider simultaneously.

20. In a shocking machine having a receptacle, the combination of a movable sheaf delivery member adapted to deliver to the receptacle a plurality of sheaves and spread them in transit, and means in the receptacle for further spreading the sheaves as they are deposited therein.

21. In a shocking machine having a receptacle, the combination of a two part sheaf delivery member held together as a unit in its normal sheaf receiving position and adapted to deliver to the receptacle a plurality of sheaves, and means for positively separating the delivery member when in transit to spread the sheaves before they are deposited in the receptacle.

22. In a shocking machine having a receptacle, the combination of a two part sheaf delivery member adapted to deliver a plurality of sheaves to said receptacle, means for holding the parts together as a unit when the member is in its normal sheaf receiving position, and means for positively separating the delivery member when in transit to spread the sheaves before they are deposited in the receptacle.

In testimony whereof I have signed my name to this specification on this 25th day of June 1923.

WILLIAM WADDELL.
